COOLING AND TRANSFER TABLE

Karl Neumann, St. Ingbert (Saar), Germany, assignor to
Moeller & Neumann G.m.b.H., St. Ingbert (Saar), Germany, a firm

Filed Apr. 16, 1957, Ser. No. 653,104

1 Claim. (Cl. 80—42)

The present invention relates to new improvements in roller cooling and transfer tables as required in rolling mills for cooling or transferring the metal sheets produced in such mills.

Cooling tables on which the metal sheets are cooled by means of rollers have the considerable advantage over those of other types that the sheets are cooled much more uniformly and efficiently and that the points of contact between the cooling table and the hot metal sheets are much smaller.

In such roller cooling tables, the transfer rollers are preferably made in the form of narrow disks or rollers of a relatively large diameter. These disks which are mounted on shafts are usually either driven directly, or they are driven indirectly by means of small friction rollers on which the transfer disks are supported.

In view of the heat radiated from the metal sheets, it has been a considerable difficulty in cooling tables of any previous type to provide a proper lubrication thereof. This is true also for roller cooling tables in which, however, the additional danger occurs that the heat transferred thereto by radiation and conduction might distort the shafts on which the transfer disks are mounted.

Another difficult problem occurring in roller cooling tables consists in the fact that all transfer disks or rollers should have the same peripheral speed in order to avoid harmful relative movements between the transfer disks and the metal sheets, and also in order to insure a transfer of the sheets in the proper direction along the cooling table.

In one prior design of a cooling table as described in the U.S. Patent No. 1,390,853, in which the transfer disks or rollers are arranged in a staggered relation to each other, these disks are mounted on continuous, directly driven shafts which are rotatably mounted in bearings.

This type of construction of a cooling table has the disadvantage that the bearings of the shafts are exposed to the heat radiated by the metal sheets and that it is therefore very difficult to provide an adequate lubrication of the bearings. Furthermore, such heat is bound to distort the long shafts on which the transfer disks are mounted and will distort them unevenly. Consequently, the upper surface of the cooling table formed by the transfer disks will no longer be level, and the table is easily subject to breakdowns in operation and will require frequent and considerable repairs.

Another known type of construction of a cooling table provides a table surface which is formed of a plurality of parallel and independently acting groups of rollers of a relatively small diameter which are driven individually or in groups by means of small friction rollers, and each pair of which is mounted on a common shaft.

This type of construction of a cooling table also has the disadvantage that the shafts on which the transfer rollers are mounted will be unevenly distorted by the heat of radiation of the metal sheets. Depending upon the type or direction of the distortion of the shafts, the

2

rollers will deviate from their vertical position, a relative movement between the peripheral surfaces of the rollers and the metal sheets to be transferred will result, and the individual units each consisting of a pair of rollers on one shaft will no longer be in balance.

Furthermore, when starting and stopping the rotation of the transfer rollers of this type of cooling table, the danger prevails that relative movements will occur between the peripheral surfaces of the driven friction rollers and the transfer rollers driven thereby, that therefore the metal sheets may not be moved in the proper direction, and that considerable wear will occur, as well as relative movements between the metal sheets and the transfer rollers.

15 This type of cooling table also has the disadvantage that for driving each transfer roller two frictional rollers are required. Furthermore, since the transfer rollers of the individual units are disposed one behind the other in straight parallel lines and are not staggered relative to 20 each other, the diameter of the rollers determines the distance between the axes of the individual rows. Therefore, if the distance between the individual rows of rollers is sufficiently small so as to insure a proper transfer even of short strips of sheet metal, the maximum diameter of 25 the rollers must necessarily be very small, with the result that the heat radiated by the metal sheets will exert a very harmful effect upon the shafts and bearings of the friction rollers.

It is an object of the present invention to provide a 30 roller cooling table for metal sheets which avoids all of the above-mentioned disadvantages of the known constructions of such tables and which particularly insures that the cooling and transfer surface formed by its rollers or disks will always be completely level.

35 This is attained according to the invention by providing a cooling surface which consists of a large number of transfer disks which are arranged in a staggered relation to each other on directly driven shafts which are rotatably mounted without intermediate axial bearings and 40 by means of small rotatable supporting rollers which do not exert any driving force upon the transfer disks or shafts, and each pair of which rotatably supports at least two adjacent transfer disks mounted on one shaft portion.

45 Another object of the invention consists in subdividing the long directly driven shafts into a plurality of shaft portions of a number and length depending upon the width of the cooling table, and in interconnecting the adjacent shaft portions by means of expansion couplings.

50 A further object of the invention consists in providing a cooling table which is designed so as to avoid any distortion of the shafts carrying the transfer disks by enclosing these shafts within tubular members which have an inner diameter larger than the diameter of the shafts.

55 For this purpose, the individual tubular members are preferably made of a length which is slightly smaller than the inner width between the hubs of two adjacent disks and so that their ends are centered on the shafts and slidably thereon.

60 Another feature of the invention consists in the provision of a paint-like coating of heat-resistant and radiation-repellent material.

Further objects, features, and advantages of the present invention will be apparent from the following detailed description thereof, particularly when read with reference to the accompanying drawings, in which—

Fig. 1 shows a plan view of a cooling table according to the invention;

70 Fig. 2 shows a cross section of Fig. 1 taken in a direction transverse to the direction of transfer of the metal sheets;

Fig. 3 shows a partial cross section similar to Fig. 2 but on an enlarged scale; while

Fig. 4 shows a cross section of the cooling table according to Figs. 1 to 3, taken in the direction of transfer of the metal sheets.

Referring to the drawings, each full shaft length of the cooling table according to the invention is divided into two separate sections of substantially equal length, each of which is driven by a separate motor M at the respective outer end thereof. The total length of each shaft section forming one-half of the width of the cooling table preferably amounts to about 55 ft. Primarily for reasons of an easier manufacture, each shaft section is subdivided into three parts or sections W₁, W₂, and W₃ which are connected to each other by means of expansion couplings K so as to permit each part of the shaft to expand freely.

Each of these directly-driven composite shafts W₁ to W₃ carries a plurality of transfer disks, for example, T₁ to T₁₄, and is rotatably mounted without any axial bearings but by means of small supporting rollers S which are freely rotatable within bearing brackets B and support transfer disks T₁ to T₁₄. As illustrated particularly in Figs. 3 and 4, each bearing bracket B carries a pair of such supporting rollers S, and each pair supports one transfer disk T at two angularly spaced points thereof, thereby also supporting and centering the composite shaft W₁ to W₃. Thus as shown in Figs. 2 and 3, two alternate disks T on each shaft portion W are supported by two sets of rollers S. The supporting rollers S are thus spaced at a considerable distance from the hot metal sheets which are transferred along their upper surface, and the bearings of these rollers S will be affected so little by the heat radiated by the metal sheets that they will not be structurally harmed, nor will their lubrication be impaired.

The adjacent transfer disks T on each shaft portion W₁ to W₃ are separated from each other by tubular members R which may consist of steel or a suitable heat-resistant material and each of which has a length slightly smaller than the distance between the hubs of the adjacent disks and an inner diameter larger than the diameter of the shaft portions C which they enclose. At regular intervals determined by the distance between the adjacent disks T, each shaft portion W₁ to W₃ has portions D of a greater diameter than shaft portions C and a greater width than the hub thickness of disks T. Disks T are secured to these shaft portions D, for example, by keys K. The outer ends of tubular members R are slidably mounted on the projecting ends of shaft portions D, and these members thus form a cylindrical air space E around each shaft portion C. The heat radiated from the metal plates will then first impinge upon these tubular members R, and since it will not immediately heat these members entirely uniformly, they will have the tendency to become slightly distorted. However, before the heat can penetrate through the tubular members R and to shaft portions C, these members will have by heat conduction become uniformly heated along their entire periphery so that whatever heat might radiate inwardly therefrom upon shaft portions C will heat the shaft so uniformly that any uneven distortion thereof will be avoided.

The heat-resistant effect of tubular members R may be further increased to a considerable extent by providing them either on the outside or on the inside, or on both sides with a paintlike coating consisting of a material which is heat-resistant and radiation-repellent. The different shaft portions may also be coated with such

material. Such coating will have the effect that the shafts will be heated very uniformly and that any uneven distortion thereof will be absolutely prevented.

If the motors M driving the various shafts W of the cooling table directly are electrically synchronized, such direct drive will absolutely insure a uniform peripheral speed of all transfer disks and prevent any relative movement between these disks and the metal sheets which are being transferred thereon.

The different means as described for protecting the shafts from distortion will insure that the transfer surface formed by the large number of transfer disks in a staggered relation to each other will always be within a perfectly level plane regardless of the speed of transfer of the metal sheets.

Since the rotatable supporting rollers which do not exert any driving force upon the shafts or transfer disks are spaced at a considerable distance from the hot metal sheets, their bearings will never become unduly heated. Consequently, these bearings will not become distorted or jam, the lubrication of these bearings will not be harmed, and they will always work perfectly. Furthermore, the particular construction and distribution of the various pairs of supporting rollers according to the invention reduces the required number thereof and therefore also the cost of production of the cooling table.

In conclusion it may once more be stated that particularly insofar as the lubrication and distortion of the various parts are concerned, the design of a cooling table according to the present invention completely and reliably overcomes the various difficulties incurred in all previous cooling tables by the heat radiated from the metal sheets conveyed thereon and it also safely prevents the occurrence of any relative movements between the transfer disks and the metal sheets which are to be transferred thereby.

Although my invention has been illustrated and described with reference to the preferred embodiments thereof, I wish to have it understood that it is in no way limited to the details of such embodiments, but is capable of numerous modifications within the scope of the appended claim.

Having thus fully disclosed my invention, what I claim is:

45 A cooling bed for cooling and conveying hot metal sheets from a rolling mill, comprising a plurality of parallel shafts, a driving means directly connected to each of said shafts, each shaft comprising a plurality of co-axial sections wherein said sections are connected to each other by expansion couplings, each shaft section having mounted thereon at least three circular transfer disks, a pair of supporting rollers engaging with alternate disks, there being at least two pairs of support rollers for each shaft section, said rollers being disposed below respective supported disks and spaced from each other in the plane of rotation of respective supported disks, and bearing means for rotatively supporting said rollers.
